(57) **CLAIM**

The ornamental design for a tibial plate wedge, as shown and described.

DESCRIPTION

FIG. 1 is a perspective view of a tibial plate wedge in accordance with the new design;

FIG. 2 is a top view of the tibial plate wedge of FIG. 1; FIG. 3 is a bottom view of the tibial plate wedge of FIG. 1; FIG. 4 is a left side view of the tibial plate wedge of FIG. 1;

FIG. 5 is a right side view of the tibial plate wedge of FIG. 1;

FIG. 6 is a front view of the tibial plate wedge of FIG. 1; and, FIG. 7 is a rear view of the tibial plate wedge of FIG. 1. In the drawings, the broken lines illustrate portions of the tibial plate wedge which form no part of the claimed design.
